CLAIM

The ornamental design for a body form for display case, as shown and described.

DESCRIPTION

FIG. 1 is a perspective view of the body form for display case according to the present application.

FIG. 2 is a front view of the body form for display case according to the present application.

FIG. 3 is a right side view of the body form for display case according to the present application. The left side view is a mirror image of the right side view.

FIG. 4 is a rear view of the body form for display case according to the present application.

FIG. 5 is a top view of the body form for display case according to the present application; and,

FIG. 6 is a bottom view of the body form for display case according to the present application.

The broken lines in all views are for illustrative purposes only and form no part of the claimed design.
